UNITED STATES PATENT OFFICE.

FRITZ CARL THEODOR MEINECKE, OF PHILADELPHIA, PENNSYLVANIA.

DESIGN FOR A TOY.

49,490.

Specification for Design.

Patented Aug. 8, 1916.

Application filed June 17, 1916. Serial No. 104,285. Term of patent 7 years.

To all whom it may concern:

Be it known that I, FRITZ CARL THEODOR MEINECKE, a citizen of the United States, residing at Philadelphia, in the county of Philadelphia, State of Pennsylvania, have invented a new, original, and ornamental Design for Toys, of which the following is a specification, reference being had to the accompanying drawing, forming part thereof.

The figure is a perspective view of a toy, showing my new design.

I claim:

The ornamental design for a toy, as shown.

FRITZ CARL THEODOR MEINECKE.
